UNITED STATES PATENT OFFICE

SAMUEL H. HIGGINBOTHAM, OF ALHAMBRA, CALIFORNIA

DESIGN FOR A COMBINATION TOOL

Application filed January 16, 1932. Serial No. 42,500. Term of patent 14 years.

To all whom it may concern:

Be it known that I, SAMUEL H. HIGGINBOTHAM, a citizen of the United States, residing at Alhambra, in the county of Los Angeles and State of California, have invented a new, original, and ornamental Design for a Combination Tool, of which the following is a specification, reference being had to the accompanying drawings, forming a part thereof.

Fig. 1 is a side elevation of a combination tool, showing my new design and Fig. 2 is an edge elevation of the same.

I claim:

The ornamental design for a combination tool, as shown.

SAMUEL H. HIGGINBOTHAM.
